UNITED STATES PATENT OFFICE.

ROBERT C. CHATTIN, OF MOUNTAIN HOME, IDAHO.

POWER-DRIVEN MOWING MACHINE.

Application filed May 9, 1921. Serial No. 467,921.

To all whom it may concern:

Be it known that I, ROBERT C. CHATTIN, a citizen of the United States, and a resident of Mountain Home, in the county of Elmore and State of Idaho, have invented a new and useful Improvement in Power-Driven Mowing Machines, of which the following is a full, clear, and exact description.

10 My invention relates to mowing machines in which a cutter blade is reciprocated by power means independently of the movement of the ground wheels, and it consists in the combinations, constructions, and arrangements herein described and claimed.

An object of my invention is to provide a device of the character described in which the operation of the cutter blade may be controlled at will.

20 A further object of my invention is to provide a device of the character described in which the speed of the driven cutter blade may be varied at will independently of the movement of the ground wheels, whereby 25 the blade may be driven rapidly or slowly according to the varying requirements of the service in which employed.

A further object of my invention is to provide a device of the character described 30 that is constructed to effect the balancing of the weight thereof on the axle of the ground wheels so that the stress on the draft animals employed to draw the device is reduced to a minimum.

35 A further object of my invention is to provide a device of the character described that is simple in construction and is not likely to get out of order or become impaired easily in service since it comprises 40 relatively few parts and no gears.

A further object of my invention is to provide a device of the character described in which the frame and cutter bar or sickle of a mowing machine of an ordinary type of 45 construction may be utilized and means required to occasion the driving of the cutter bar removably secured upon the frame in a short time and with the use of but a few tools.

50 Other objects and advantages will appear in the following specification, and the novel features of the invention will be particularly pointed out in the appended claim.

My invention is illustrated in the accom-

panying drawings, forming part of this application, in which—

Fig. 1 is a plan view of the device,

Fig. 2 is a rear view of the same after portions thereof have been removed for clearance,

Fig. 3 is a plan view of a fragmentary portion of the device,

Fig. 4 is a bottom perspective of an engine frame embodied in the device,

Fig. 5 is a sectional detail of a clutch mechanism embodied in the device, and

Fig. 6 is a sectional detail of another portion of the device.

In carrying out my invention, I provide a frame indicated generally at 1. The frame 70 1 is formed to provide a housing 2 for an axle 2' having mounted on the ends thereof ground wheels 3. A housing 4 is also provided for a pitman shaft 5 having a disk 6 at its forward end. A pitman 7 is connected at one end by a wrist pin 8 to the disk 6 and at its other end to a cutter blade or sickle bar 9 that is arranged to co-act with a blade 10 carried by a frame 11. The latter is hinged at one end to members secured to the frame so that the frame 11 may be positioned in a horizontal plane adjacent to the surface being traversed or swung about its hinged connection into a vertical plane. A seat 12 is carried by a post 13 secured to the frame. 80 85

The parts described so far are ordinary in construction and in carrying my invention into effect, I may make use of a well known type of mowing machine and may remove 90 parts therefrom until only the parts enumerated remain.

I mount upon the frame 1 a frame 14 adapted to support an engine 15 which may be of any well known type of construction. 95 The frame 14 is preferably made of metal cast in a single piece and is formed with depending bosses or extensions 16 and 17. The boss or extension 16 is curved at 18 to conform with the upper surface of the axle 100 housing 2 and the boss 17 is curved at 19 to fit the pitman shaft housing 4. The engine frame 14 is arranged with a depending integral lug or extension 20 at one end of the axle housing 2. The bosses or extensions 16 and 17 rest upon the axle housing 2 and the pitman shaft housing 4, respectively, and serve as saddles for the body of the frame 105

14. The extension 20 is formed with an opening 21 through which the axle 2' passes. A lug 22 integral with the body of the frame 14 is disposed between upstanding lugs 23 and 24 that are usual parts of the frame 1. A bolt 25 is projected through registering openings in the lugs 23, 22 and 24. The frame 14 is further secured in place by straps or yoke bands 26 secured to the bosses 16 and 17 by cap screws or bolts 27 in order to clamp the bosses 16 and 17 to the axle housing 2 and the pitman shaft housing 4, respectively. It will be noted that the bosses 16 and 17 have openings 28 in their faces adapted to receive the bolts 27. The wall of the opening 21 serves as a bearing for the main axle and also tends to maintain the frame 14 in a desired position on the frame 2 with respect to the pitman shaft 5. A spacing sleeve 29 is disposed on the axle 2' between the lug 20 and the adjacent wheel 3.

15. A pair of supporting members 30—30 are secured to the frame 1 as at 31—31 and 32—32 and extend rearwardly thereof as shown. A tank 33 adapted to contain water or a like fluid is mounted on a platform 34 that is secured to the supporting bars adjacent to the rearward ends of the latter. A fuel tank 35 is mounted upon the tank 33, being supported by arms 36—36 secured to the latter. A supply conduit 37 and a return conduit 38, which may have the form of flexible tubes, connect the tank 33 with the engine 15. The latter is provided with ordinary means (not shown) for causing the circulation of liquid from the tank 33 through the walls of the engine to cool the latter in accordance with the general and well known practice. It is to be noted that the engine 15 is rigidly secured to the engine frame 14, bolts 39 being projected through the base of the latter and through openings 40 in the frame 14. A conduit 41 is provided for conducting fuel from the tank 35 to the engine 15.

16. The engine 15 has a drive shaft 42 and a suitable clutch mechanism is connected therewith. In the present instance, the clutch mechanism comprises an inner cone 43 rigidly secured to the drive shaft and an outer friction pulley 44 having a hub 45 slidable on the shaft. The outer friction pulley 44 is normally maintained in clutching engagement with the inner cone by a spring 46 (see Fig. 5). The hub 45 is threaded exteriorly and a sprocket 46' is screwed there-

17. on, being tightened when turned in the direction opposite to that normally taken by the drive shaft. A bearing 47 for the drive shaft extends between the engine 15 and the hub 45 and has a pin 48 projecting through a guide slot 49 in a concentric outer sleeve 50. The latter is provided with a handle 51 operable from the driver's seat, whereby the sprocket 46' may be thrown into and out of engagement with the drive shaft 42 at will.

18. A sprocket wheel 53 is mounted on the end of the pitman shaft 5 and is arranged to rotate therewith, being secured by rivets 54 to the flange of a sleeve 55 that is mounted 70 on the pitman shaft 5 and secured thereto by a pin 56 or the like. A chain 57 operatively connects the sprockets 46' and 53 and passes through recesses 58 and 59 in the rear end wall of the frame 14 without contacting the 75 latter.

19. From the foregoing description of the various parts of the device, the operation thereof may be readily understood. The cutter bar is driven independently of the 80 movement of the ground wheels. The only work to be performed by the draft animals hitched to the machine is to draw the same. The cutter mechanism is operated at a uniform speed which may be varied as the occasion requires. The supporting members 85 30—30 extend rearwardly of the frame 1 and the tanks 33 and 35 are supported thereby at a spaced distance from the connection of the frame 1 with the axle 2', whereby a balanced 90 construction is obtained and the weight of the entire device is imposed directly upon the axle and not partially upon the draft animals, as is ordinarily the case.

20. A chain guard 60 for the sprocket 53 prevents the fouling of the latter by cut hay or the like.

I claim:

21. A mowing machine comprising a frame provided with a transverse axle housing, an axle rotatably mounted in said housing, a pair of wheels for supporting said axle, a cutter blade carried by said frame, an auxiliary frame secured to said first named frame directly over said housing, and an engine for driving said cutter blade, mounted on said auxiliary frame, the weight of said engine and its associated mechanism together with the cutter blade and its associate mechanism, being evenly distributed on both 110 sides of said axle.

ROBERT C. CHATTIN.
